[57] **CLAIM**

The ornamental design for a combined bottle and cap, as shown and described.

DESCRIPTION

FIG. 1 is a front elevation of a combined bottle and cap showing my new design, the rear elevation is a mirror image thereto;

FIG. 2 is a side elevation thereof

FIG. 3 is an opposite side elevation thereof

FIG. 4 is a top plan view thereof

FIG. 5 is a bottom plan view thereof

FIG. 6 is a front elevation of a second embodiment of the design, the rear elevation is the same except that the rear of the cap does not have the semicircular recess shown on the front of the cap;

FIG. 7 is a right side elevation of the second embodiment, the left side elevation is a mirror image thereto;

FIG. 8 is a top plan view thereof

FIG. 9 is a bottom plan view thereof

FIG. 10 is a front elevation of a third embodiment of the design, the rear elevation is the same;

FIG. 11 is a side elevation thereof; the sides being symmetrical.

FIG. 12 is a top plan view thereof.

FIG. 13 is a bottom plan view thereof.

FIG. 14 is a front elevation of a fourth embodiment of the design, the rear elevation is the same except that the rear of the cap does not have the recessed surfaces shown at the top and front edge of the cap;

FIG. 15 is a right side elevation of the fourth embodiment, the left side elevation is a mirror image thereto;

FIG. 16 is a top plan view thereof; and,

FIG. 17 is a bottom plan view thereof.
